MULTIPLE OPERATED FASTENING
INSTALLATIONGustav Johnson, West Roxbury, Mass., assignor
to United-Carr Fastener Corporation, Cam-
bridge, Mass., a corporation of Massachusetts

Application April 18, 1931, Serial No. 531,120

7 Claims. (Cl. 24—205)

My invention aims to provide improvements in multiple operated fastening installations and particularly improvements in separable end fastening means which permit complete separation of the stringers of the installation.

In the drawing which illustrates a preferred embodiment of my invention:—

Figure 1 is an enlarged plan view of a portion of a multiple operated fastening installation showing my improved end fastening means;

Fig. 2 is a section taken on the line 2—2 of Figure 1;

Fig. 3 is a plan view of the end portion of the installation showing the slider in plan section and in the proper position for engagement and disengagement of the end fastening means; and

Fig. 4 is a view similar to that shown in Fig. 3, but with the slider out of proper relation to the female member of the end fastening means but being moved toward it by means of the male member which has been entered into the slider.

Referring now to the particular embodiment of my invention which is illustrated by the accompanying drawing, I have shown a multiple operated separable fastening means which is particularly adapted for closures which must be completely separated at both ends at specified times. In the installation illustrated I have shown two stringers 1 and 2 to the adjacent edges of which are attached series of fasteners 3 of any suitable construction for uniting the edges of the stringers. The usual slider 4 is provided for engaging and disengaging the fasteners 3 as is now well understood by those skilled in the art.

At adjacent ends of the stringers 1 and 2 close to the ends of the rows of fasteners 3 I have provided end fastening means comprising a female member secured to the stringer 1 and a male member secured to the stringer 2. These members are adapted to be separated by passage of the male member through one side channel of the slider 4 and to be engaged by entrance of the male member into the slider only when the slider is located in a particular relation to the female member as will be hereinafter more fully described.

The male member is made of sheet metal and has an integral tubular portion 5 of substantial length beginning adjacent to the edge of the stringer 2 to which a series of fasteners 3 is attached. Extending inwardly from the tubular portion 5 in spaced relation are two flanges 6 and 7 (Fig. 2) of substantial area which are clamped against opposite faces of the stringer

to hold the male member in fixed relation to the stringer. A convenient means of attachment includes a number of prongs 8 pressed from the material of the flange 6 and passing through the stringer 2 and flange 7, the ends being upset as illustrated in Figs. 1 and 2. Adjacent to that end of the tubular portion 5 of the male member I have provided a lateral projection 9 which is adapted to cooperate with the fasteners 3 in such a manner (Fig. 3) that improper engagement of the fasteners 3 is impossible. The other end 5a of the tubular portion 5 is rounded to ride easily over the ends of the fasteners 3 (Fig. 4) and to enter easily into engagement with the female member.

The female member has a tubular portion 10 which is located adjacent to one end of a series of fasteners 3 secured to the stringer and is held in position by flanges 11 and 12 extending inwardly therefrom in spaced relation and gripping the stringer 1 between them. These flanges 11 and 12 are held in position by prongs 13 in the same manner as the flanges 6 and 7 of the male member. A slot 14 (Fig. 3) is cut into the outer edge of the tubular portion 10 to permit entrance of the flanges 6 and 7 when the male member 5 is entered into the female member 10. The slot 14 does not extend the entire length of the portion 10 thereby leaving a shoulder 15 which provides a stop against which the flanges 6 and 7 may engage to limit the entrance of the male member into the socket.

If we assume that the stringers are separated, the end members may be readily engaged no matter where the slider is located on the stringer 1. This is demonstrated by Figs. 3 and 4 of the drawing which show (Fig. 4) the slider spaced from the end member 10 and the end member 5 entered therein. By moving the stringer 2 toward the left (Fig. 3) the member 5 and slider 4 are moved to a position where the slider 4 first contacts with the cam shaped edges 16 provided in the flanges 11 and 12 of the female member by cutting slots or grooves in the said flanges. These cam edges 16 guide the slider 4 into proper relation to the fastener members 3 and female member on the stringer and the slider is, therefore, held against any substantial lateral or rocking movement. In this manner the male member 5 is easily and accurately pulled into engagement with the female portion 10 and the end members assume positions as shown in Fig. 1. The edges of the flanges 6 and 7 contact with the shoulder 15 on the portion 10 and the upper edge 5b engages beneath the last fastener 3 on 55

the stringer 1, thus properly positioning the fastener members 3 so that the slider when pulled toward the right (Fig. 1) will engage them. In this manner the ends of the stringers 1 and 2 are properly locked together and cannot be separated by stresses exerted in any direction. If an attempt is made to engage the fasteners 3 on the opposed stringers 1 and 2 while the parts are in the positions, as shown in Fig. 3, the lateral projection 9 on the member 5 would engage the ends of the fasteners 3 on the stringer 1 and any attempt to move the slider 4 to the right would result in the parts becoming "jammed". Therefore, my device is "fool-proof" to the extent that the end fasteners must be properly engaged before the slider can be operated to engage the fasteners 3 on one stringer with the fasteners 3 on the other stringer.

Separation of the stringers is easily and quickly effected by simply pulling the slider 4 towards the end members and then moving the stringer 2 longitudinally relative to the stringer 1 to pull the male portion 5 through the slider.

My end members are made in one-piece units from sheet metal and are simple and durable in construction, inexpensive to manufacture and easy to attach.

While I have illustrated and described a preferred embodiment of my invention, I do not wish to be limited thereby, because the scope of my invention is best defined by the following claims.

I claim:

1. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a male member attached to one of said stringers adjacent to one end of a series of fastening elements, a female member attached to the other stringer adjacent to one end of the series of fastener elements secured thereto, one of said members having attaching means in the form of spaced flanges engaging opposite faces of its respective stringer to secure the said means in position, said flanges having groove and cam means engaging and holding the slider in proper relation to the said member when entered into said groove thereby to permit the other member to be engaged therewith or disengaged therefrom easily and unobtrusively through the slider.

2. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a male member attached to one of said stringers adjacent to one end of a series of fastening elements, a female member attached to the other stringer adjacent to one end of the series of fastener elements secured thereto, said female member having attaching means in the form of spaced flanges of substantial area engaging opposite faces of its respective stringer to secure the said means in position and said attaching means having cam and groove means adapted to position and hold the slider in proper relation thereto, thereby to permit the male mem-

ber to pass through the slider for engagement with or disengagement from said female member without interfering with the fastening elements on the stringers.

3. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a male member attached to one of said stringers adjacent to one end of a series of fastening elements, a female member attached to the other stringer adjacent to one end of the series of fastener elements secured thereto, each of said members having attaching means in the form of spaced flanges of substantial area engaging opposite faces of their respective stringers to secure the said means in position, slider positioning means provided by the attaching means of one of said end members and attaching prongs extending from one flange of each member through a stringer and clenched into engagement with the other flange.

4. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a male member attached to one of said stringers adjacent to one end of a series of fastening elements, a female member attached to the other stringer adjacent to one end of the series of fastener elements secured thereto, each of said members being substantially straight throughout its length and one member having a lateral projection extending toward the other member to provide interfering means to prevent improper fastening engagement of the end fastener elements of the stringers and cam and groove means provided by said female member for positioning the slider in proper relation thereto, thereby to permit the male member to pass through the slider for engagement with or disengagement from said female member, said male member being in the form of a single rigid member of substantial length extending along an edge of one of the stringers and having one end located relatively close to the last fastener element on that stringer.

5. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a male member attached to one of said stringers adjacent to one end of a series of fastening elements, a female member attached to the other stringer adjacent to one end of the series of fastener elements secured thereto, said female end member having a tubular portion offset laterally beyond the edge of one of the stringers to receive the male member and having plate-like attaching means engaging the stringer, said plate-like attaching means having a notch cut therein to permit passage of part of the female end member into the slider.

- so that the slider may assume a proper position with relation to the tubular portion when the end fastening means are being engaged or disengaged.
5. 6. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a male member attached to one of said stringers adjacent to one end of a series of fastening elements, a female member attached to the other stringer adjacent to one end of the series of fastener elements secured thereto and each of said end members being formed from a single piece of metal and having 10 attaching means of substantial area securing them to their respective stringers, said attaching means extending upwardly along said stringers substantial distances beyond the first fastener element on each stringer and attaching 15 20 25 prongs extending from said attaching means through the stringers and upset to secure the end fastening members to the stringers.

7. In a multiple operated fastening device having two stringers each having a series of fastening elements attached to an edge, a slider for engaging and disengaging the fastening elements at one edge of one stringer with the fastening elements at an edge of the other stringer and end fastening means whereby said stringers may be completely disengaged, said end fastening means comprising a relatively long straight male member attached to one of said stringers adjacent to one end of a series of fastening elements and having its axis parallel with the edge of the stringer, a female member attached to the other stringer adjacent to one end of the series of fastener elements secured thereto and having its axis parallel to the edge of said other stringer, and one of said members having a rigid projection for a portion of its length only at the end nearest the fastening elements and extending laterally toward the other beyond the remainder of said member to provide 20 interfering means to contact with the fastening elements for preventing improper fastening engagement of the fastening elements on the stringers in the manner described.
